SCRATCHERS

Jesse E. Hall, Sr., Weatherford, Tex.

Application March 27, 1953, Serial No. 345,069

5 Claims. (Cl. 166—173)

This invention relates to improvements in scratchers and refers more particularly to abrading or scratching elements formed of circular bands of metal from which extend flexible wire tines or whiskers and sometimes employed in the conditioning of the well bore of an oil well. The salient novelty in the present invention resides in the use of prominences or protuberances on the outer surface of the band or collar to facilitate the movement of the wires with respect to each other and with respect to the collar when the collar is reciprocated with the tubing or casing in the well.

Scratchers or abrading devices have been used principally in the conditioning of oil wells prior to cementing to scrape off the filter cake deposited thereon during the drilling operation and thereby obtain a more satisfactory bond between the cement and the earth formations. These scratchers are preferably in the form of collar supports to which are flexibly attached abrading wires which extend nonradially from the support. The collars of the scratchers are mounted rotatively and with a limited axial movement on the casing or pipe to permit easy reversal upon reciprocation of the casing in the well.

In running the pipe into the well and during the down-stroke of reciprocation, the abrading wires are inclined upwardly while on the upstroke they are inclined downwardly. In this connection it will be understood that the normal outside diameter of the scratchers is considerably more than the well bore diameter, and accordingly when introduced into the well bore the wires are confined within the narrow annular space between the casing or pipe and well bore so as to have relatively strong frictional contact with the well wall at all times during reciprocation.

A weakness in the structural design of scratchers of this type is the tendency for the abrading wires during reciprocation to foul and wrap around the adjacent wires as the scratcher is moved up and down with the casing during reciprocation. The difficulties arise either from the crossing of adjacent wires or from the wires becoming entwined or engaged with either the coil springs from which the wires extend or upon other obstructions which extend above the surface of the collar or support. To correct this difficulty of fouling the wires and twisting them into shapes in which they do not function normally, there are located upon the support or collar, prominences or protuberances at intervals circumferentially thereof and in definite relationship with the projection point of the wires. These raised portions are so positioned with respect to the projection points of the wires that they permit a relatively unobstructed override of the wires during the reciprocation of the collar support. Descriptive of the location of the prominences it might be said that they are positioned upstream of the projection points of the wires since the wires are angularly disposed to the collar and may be said to project downstream therefrom.

An advantage therefore of the invention is to provide a scratcher comprising a collar adapted to be rotatably mounted upon a pipe or casing with abrading elements extending nonradially from its periphery and prominences

2

or mounds arranged upon the outer surface of the collar which facilitate unobstructed passage of the wires throughout substantially a 180° arc from an upright position substantially parallel with the axis of the collar to a depending position also substantially parallel with the collar's axis.

Another advantage is the provision of protuberances upon the surface of the collar support located on the opposite side of the coils from the direction which the wires project and closely adjacent to the projection points to permit a relatively unobstructed override of the wires as the collar is reciprocated.

A further advantage is to provide a plurality of coil springs interposed in the individual wires at their points of projection with prominences or protuberances formed on the collar adjacent said coil springs to prevent fouling of the wires with the other coil springs on movement of the collar during reciprocation.

Other objects and advantages of the invention will be apparent from the description which follows.

In the accompanying drawings which form a part of the instant specification and are to be read in conjunction therewith and in which like reference numerals are used to indicate like parts in the various views:

25 Fig. 1 is a side elevational view of a scratcher embodying the invention with parts shown in section;

Fig. 2 is a view of one-half the scratcher shown in Fig. 1 partly in plan and partly in section.

Fig. 3 is a detail showing a modified form of protecting protuberance or prominence eliminating the flat top structure; and

Fig. 4 is a second modification of a protective prominence or protuberance which extends across the collar between two of the supporting wires.

35 Referring to the drawings, at 10 is shown a collar support which is circular in form and is pressed from a strip of sheet metal and welded together at its ends. At intervals around the circumference of the collar are lanced out by punching tabs or tongues 11 which serve as the gripping or anchoring members for the abrading wires. The wire abrading elements which are in the form of tines or whiskers extend from the collar in two circumferential rows; the wires in the upper row designated by the numeral 12a and the tines or whiskers in the lower row designated by the letter 12b. Interposed in the wires at the points of projection from the collar are coils 12c.

Crossover sections of the wires between the coils 12c which in the construction shown lie within the collar are designated 12d. These crossover sections are gripped 50 beneath the anchoring tabs or tongues 11. Holes are punched in the collar and located so the coils formed in the wires extend through the holes, as best shown in Figs. 2 and 3.

55 Adjacent each of the coil springs and on the opposite side from which the wires project are prominences, preferably at least as high as the height of the coils above the periphery of the collar. These prominences may be formed by pressing out the metal of the collar itself or may be applied as separate pieces of metal welded or

60 otherwise fastened to the exterior surface of the collar. In Fig. 1 the prominences or bosses 13 are frusto-conical in shape with a flattened top 13a and are cut away at one side by the perforations in which the coil springs 12c are positioned thereby giving the prominences or bosses a crescent-shaped contour. The purpose of flattening the tops of the prominences is to reduce in so far as possible the outside diameter of the collar support, since under tight bore hole conditions the less the diameter of the collar the less is the abrasive wear upon the collar support and the better is the protection afforded to the coil springs and abrading wires.

70 The protective prominences 14 shown in Fig. 3 are

varied from the structure shown in Fig. 1 in that the flattened top 13a has been eliminated and a dome shape adopted.

The prominences or protuberances 15 shown in Fig. 4 are formed in or applied to the outer surface of the collar and extend continuously between the upper and lower rows of wires simulating spectacles in shape. These protective prominences likewise have a flattened top 15a to reduce as much as possible the diameter of the support.

In operation a plurality of the scratchers are mounted upon the exterior of a pipe or casing. The scratcher collars have a slightly greater internal diameter than the external diameter of the pipe upon which they are mounted. Lugs or stops are welded to the pipe above and below the collars permitting a limited longitudinal movement of the collars along the pipe and free rotation of the collars upon the pipe. The intervals at which the scratchers are positioned along the pipe is usually governed by the length of stroke of reciprocation given the pipe during the conditioning operation.

As suggested hereinbefore, as the pipe is run into the well, there is an annular space between the pipe and well bore having a width considerably less than the distance that the wires extend from the exterior of the collar. As a consequence, as the casing or pipe is run in, the wires frictionally engage the wall of the well and the abrading elements or tines drag or are inclined upwardly as the casing is moved downwardly into the well. When the casing or pipe arrives at the location where it is to be set or where the well wall is to be cleaned of mud cake, the pipe is reciprocated in the well bore for a distance upwardly and downwardly corresponding substantially to the distance between the scratchers. Thus, the well wall is abraded by the scratcher wires throughout the zone to be conditioned. During the downstroke the stops above the collars of the scratchers contact the top rim of the collar until the direction of the pipe is reversed. Upon reversal of the direction of the pipe or as the upstroke commences, the lugs below the collar contact the lower rim of the collars and the wires or abrading elements pivot at their ends in the well wall causing the collars to pass through the wires while they are being held closely against the periphery of the collars.

Due to the fact that the wires extend nonradially from the collar, all in the same direction, and are closely wrapped about the periphery of the collar on account of their confinement within the narrow annular space between the pipe and well bore, it is inevitable that the wires will foul or become entwined with each other or with the coil springs from which the wires extend unless some provision is made for them to override freely. This is accomplished by strategically locating the protuberances or prominences upon the outer surface of the collar at locations which permit a relatively unobstructed override of the wires and the coils from which the wires extend. Upon each reciprocation of the pipe and reversal of the scratcher wires, this difficulty arises, since with each stroke of the casing, the collar reverses its travel and must pass through the wires in a reverse direction. This necessitates a structure that will permit the wires to freely override the adjacent wires and coils when the scratchers are moved in either direction during reciprocation. Entanglement of the wires with each other or with the coils not only destroys their usefulness and function but exposes them to the abrasive action of the well bore causing failure and almost immediate destruction of wires as operative elements of the scratcher.

Thus it will be seen that there has been provided a scratcher construction having protective mounds or protuberances upon the periphery of the collar support which will permit a relatively unobstructed passage of the collar through the wires during reciprocation of the scratchers with a minimum of fouling or entanglement of the wires, either upon themselves or upon the coil springs from which they extend.

It will be understood that certain features and subcombinations are of utility and may be employed without reference to other features and subcombinations. This is contemplated by and is within the scope of the claims.

It is further obvious that various changes may be made in details within the scope of the claims without departing from the spirit of the invention. Therefore it is to be understood that the invention is not limited to the specific details shown and described.

Having thus described my invention, I claim:

1. In a well-bore cleaning scratcher, a circular collar 10 dimpled interiorly to form integral raised bosses on its exterior surface, said bosses being at circumferentially spaced intervals around the collar, said collar having an aperture beside each boss, all of said apertures being circumferentially offset in the same direction from the respective bosses, and a plurality of coil mounted abrading wires, each having its coil located in one of said apertures with the wire projecting away from the adjacent boss to a point beyond but spaced outwardly from the next boss, whereby all of said wires have a sidewise inclination in the same direction relative to said collar.
- 20 2. A scratcher as in claim 1 wherein each aperture intersects the associated boss whereby part of the aperture extends through the boss and the balance extends through a portion of the collar adjacent to the boss.
- 25 3. In a well bore cleaning scratcher, a circular collar containing a series of apertures, said apertures being at circumferentially spaced intervals around the collar, a plurality of abrading wires each extending through one of said apertures and having a portion secured to the interior 30 of the collar adjacent to such aperture, each wire being coiled at the point where it passes through the associated aperture to form a spring, said collar having beside each aperture an integral boss raised on its exterior surface, all of said bosses being circumferentially offset in the same direction from their respective apertures, the height of each boss being at least equal to the distance that the coil in the adjacent aperture projects out of the aperture, thereby to form a shield on one side of such coil, and each wire extending exteriorly of the collar away from its 35 shielding boss to a point beyond but spaced outwardly from the next boss, whereby all of said wires have a sidewise inclination in the same direction relative to said collar.
- 40 4. A scratcher as in claim 3 wherein each boss is frustoconical in shape.
- 45 5. A scratcher as in claim 3 wherein each boss is generally crescent-shaped and has the coil of the associated wire located in the concave side of the crescent.
